UNITED STATES PATENT OFFICE.

VICTOR E. BERGSTROM, OF NEW YORK, N. Y.

COMBINED CLIPPER AND HAIR-CUTTING SCISSORS.

1,207,476.

Specification of Letters Patent. Patented Dec. 5, 1916.

Application filed August 4, 1915. Serial No. 43,653.

To all whom it may concern:

Be it known that I, VICTOR E. BERGSTROM, a citizen of the United States, residing at New York, in the county of New York and 5 State of New York, have invented new and useful Improvements in Combined Clippers and Hair-Cutting Scissors, of which the following is a specification.

The invention relates to a combined clipper and scissors, presenting a structure adapted for operation in one position to provide an accepted type of clipper and in operation in a reverse position to provide an ordinary form of scissors.

15 The improved device contemplates a simple comparatively small structure of little or no complication in which the parts are arranged to permit the maximum efficiency in either use, the operation of the parts 20 being practically identical with that of the well known clippers or scissors.

The invention in the preferred form of details will be described in the following specification, reference being had particularly to the accompanying drawings, in 25 which:

Figure 1 is a plan of the improved device; Fig. 2 is a one edge view of the same; Fig. 3 is an opposite edge view of the same; 30 Fig. 4 is a section on line 4—4 of Fig. 1; Fig. 5 is a section of a detail.

The improved implement comprises what may be termed a main plate 1 of approximately rectangular shape in plan being reduced at one end to provide a handle portion 2 terminating in the usual finger grip 3. The main plate for the greater portion of its length is reduced in thickness as at 4, the cut away portion extending from a 35 point above one edge of the plate to and through the opposite edge and from the free end of the plate to a point a slight distance in advance of the handle portion 2. This formation presents in effect a recess in the 40 plate having abrupt shoulders 5 and 6 forming the longitudinal and transverse walls of the recess. The outer surface of the main plate from a point above the shoulders 5 to the extreme lower edge of the plate 45 is beveled as at 7, while the inner surface of the plate beyond the shoulder is smooth, intersecting the inclined edge 7 to form a shearing edge 8. The edge of the plate remote from the shearing edge 8 is formed 55 to provide the usual cutting teeth 9 com-

mon to clipper construction. The coöperating clipper member comprises a clipper plate 10 of a size to fit in the recess 4, the plate being of less length than the length of the recess, being equal in thickness to 60 the depth thereof so that the inner surface of the clipper plate is approximately in line with the inner edge of the main plate below the shoulder 5. The clipper plate is formed with elongated slots 11 to receive 65 set screws 12 which seat in openings 13 in the main plate, so that the clipper plate is mounted for sliding movement longitudinally of the main plate. The recesses are preferably formed so that the heads of the 70 screws are seated flush or below the proximate faces of the clipper plate to avoid projection. That edge of the clipper plate remote from the shoulder 5 is formed with clipper teeth 14 to coöperate with the teeth 75 9 so that in the reciprocation of the clipper plate on the main plate a clipping operation is secured. A pivot pin 15 is mounted in the main plate beyond the recess 4 and on this pin is supported a finger lever 16 80 of approximately angle formation, the free end of the lever having the finger hold or grip 17. At the juncture of the angle sections of the finger lever there is pivotally secured one end of a link 18, the opposite 85 end of which is pivotally connected at 19 to the clipper plate. By this construction movement of the finger lever in obvious operation will reciprocate the clipper plate and thereby cause such coöperation of the 90 gripping teeth as is desired in implements of this type.

Pivottally mounted on the pivot pin 15 is an auxiliary member 20 in the form of a scissors blade, the forward or blade portion 95 21 of which is shaped to shearingly coöperate with the cutting edge 8 of the main plate, the blade in this operation bearing against the inner surface of the main plate below the shoulder 5. The auxiliary member terminates in a handle portion 22 arranged to coöperate with and in all respects similar to the handle portion of the main plate.

As thus constructed and arranged it is obvious that the operation of the finger lever 105 in conjunction with the main plate produces a clipping operation, while the actuation of the respective handles 2 and 22 produce a scissors operation. If desired the handle 2 may be provided with a catch 23 of any 110

appropriate type whereby the finger lever may be locked in inoperative relation when the device is in use as a scissors.

What is claimed is:

- 5 1. A combined clipper and scissors including a main plate formed with a recess, and provided beyond the recess with a handle portion, one edge of the plate being formed with clipper teeth, the opposite edge of the teeth being formed with a shearing edge, a clipper plate slidably mounted in the recess of the main plate and having clipper teeth to coöperate with the clipper teeth of the main plate, a finger lever pivotally mounted in the main plate and connected with the clipper plate, and an auxiliary member pivotally mounted in the main plate and having a shearing edge portion to coöperate with the shearing edge of the main plate.
- 10 15 2. A combined clipper and scissors including a main plate formed with a recess, and
- 20

provided beyond the recess with a handle portion, one edge of the plate being formed with clipper teeth, the opposite edge of the teeth being formed with a shearing edge, a ² clipper plate slidably mounted in the recess of the main plate and having clipper teeth to coöperate with the clipper teeth of the main plate, a finger lever pivotally mounted in the main plate and connected with the ³ clipper plate, and an auxiliary member pivotally mounted in the main plate and having a shearing edge portion to coöperate with the shearing edge of the main plate, and means to hold the finger lever inoperative when desired.

In testimony whereof I affix my signature in presence of two witnesses.

VICTOR E. BERGSTROM.
